(57) **CLAIM**

The ornamental design for a dimensioning system, as shown and described.

DESCRIPTION

FIG. 1 is a perspective view of a dimensioning system showing our design;

FIG. 2 is a front view of our design;

FIG. 3 is a rear view thereof;

FIG. 4 is a right side thereof;

FIG. 5 is a left side thereof;

FIG. 6 is a top plan view thereof; and,

FIG. 7 is a bottom plan view thereof.

The broken lines in the drawing figures are for illustrative purposes only and do not form a part of the claimed design.
